UNITED STATES PATENT OFFICE.

JOHN F. SHOEMAKER, OF DES MOINES, IOWA.

CHECK-BOOK.

1,230,044.

Specification of Letters Patent. Patented June 12, 1917.

Application filed October 18, 1915. Serial No. 56,485.

To all whom it may concern:

Be it known that I, JOHN F. SHOEMAKER, a citizen of the United States, residing at Des Moines, in the county of Polk and State 5 of Iowa, have invented certain new and useful Improvements in Check-Books; and I do hereby declare the following to be a full, clear, and exact description of the invention, such as will enable others skilled in the art 10 to which it appertains to make and use the same.

The invention relates to improvements in check books.

The object of the present invention is to 15 improve the construction of check books and to provide a simple, practical and comparatively inexpensive check book designed principally for use in connection with safety bank checks forming the subject matter of 20 a co-pending application filed April 12th, 1915, Serial #20,908, and equipped with means for enabling the proper amount to be indicated by the coupon or extension to be readily torn off with absolute accuracy.

25 With these and other objects in view the invention consists in the construction and novel combination and arrangement of parts hereinafter fully described, illustrated in the accompanying drawings and pointed out 30 in the claims hereto appended, it being understood that various changes in the form, proportion and minor details of construction may be resorted to without departing from the spirit or sacrificing any of the advantages of the invention.

In the drawings—

Figure 1 is a plan view of a desk check book constructed in accordance with this invention and shown open, a portion of one 40 of the covers being broken away,

Fig. 2 is a sectional view taken substantially on the line 2—2 of Fig. 1 illustrating the manner of mounting the cutter,

Fig. 3 is a sectional view taken longitudinally of the check book and illustrating the manner of binding the checks,

Fig. 4 is an enlarged detail sectional view on the line 4—4 of Fig. 1,

Fig. 5 is a plan view of a portion of a 50 pocket check book,

Fig. 6 is a longitudinal sectional view of the same.

Like numerals of reference designate corresponding parts in the several figures of 55 the drawings.

In the accompanying drawings, in which

is illustrated the preferred embodiment of the invention, the desk check book comprises in its construction covers 1 and 2 of any desired construction and either plain or ornamental or expensive and connected by a flexible portion or back 3. The back 3 is provided at its inner face with a pocket 4 extending from the top to the bottom of the cover 2 and adapted to receive a leaf binder 65 tongue or element 5 constructed of suitable flexible material such as paper lined with cloth and folded vertically to form binding portions 6 and 7 adapted to receive the stubs 8 of checks 9. The binding portion 7 is 70 formed by a fold as shown and the stubs of the checks are detachably secured between the binding portions of the binder tongue by a metal strip or staple 10 arranged on the exterior of the clamping portion 6 and 75 having its terminals passed through slots 11 and 12 of the binding portions and through the stubs of the checks and bent outwardly in opposite directions or clenched at 13 against the clamping portions 7 as 80 clearly illustrated in Fig. 4 of the drawings. The metallic fastening strip 10, by having its terminal portions passed through the slots of the binding tongue and the stubs, detachably secures the stubs and checks to 85 the cover and after the checks have been used the terminal portions 13 may be bent back and the metallic strip removed to permit the stubs to be detached and another series of checks to be secured in the cover. 90 The leaf binder element is detachably fitted in the pocket 4 as illustrated in Fig. 3 of the drawings and it will enable a number of loose checks to be readily applied to the covers 1 and 2. This will enable banks to 95 supply covers and leaf binders to their depositors and as the sheets or blank checks may be readily bound in the covers, the bank may obtain such sheets or checks unbound and supply them to their depositors as required and the expense of supplying such check books and checks will be materially decreased.

The cover 1 is equipped with a check cutter 14 consisting of a strip of metal or other 105 suitable material extending vertically across the inner face of the cover 1 of the desk check book and having its terminals fitted in pockets 15 and 16 formed in the cover 1 near the upper and lower edges thereof. 110 The cutter is provided with a reduced upper portion forming an inclined shoulder

- 17 which corresponds to the inclination of the spaces of the extension of the check. The cutter 14 is adapted to be readily sprung into and out of engagement with 5 the vertically aligned pockets 15 and 16. A cutter 24 may be arranged in longitudinally aligned pockets 18 and 19 of a pocket check book 23, consisting of a number of checks bound in the front cover in the usual manner. 10 The pockets 18 and 19 are preferably formed by strips 20 and 21 secured to and extending across the inner and outer ends of the covers 22 of the pocket check book 23. By having a removable cutter adapted to be transferred 15 from one check book to another, only one cutter need be supplied to a depositor.

What is claimed is:—

1. A check book provided at the inner face of one of its covers with a cutter consisting of a strip of thin material connected at its ends with the cover within the marginal edges of the latter, said cutter being arranged in close proximity to the inner face of the cover and permitting a check to be passed between it and the said cover. 20 2. A check book provided at the inner face of one of its covers with a cutter consisting of a strip of thin material connected at its ends with the cover within the marginal edges of the latter, said cutter being arranged in close proximity to the inner 25 30 face of the cover and permitting a check to be passed between it and the said cover.

face of the cover and permitting a check to be passed between it and the said cover, and provided at a point intermediate of its ends with a shoulder.

3. A check book provided at the inner face of one of its covers with a cutter consisting of a strip of thin material connected at its ends with the cover within the marginal edges of the latter, said cutter being 40 arranged in close proximity to the inner face of the cover and permitting a check to be passed between it and the said cover, and provided at a point intermediate of its ends with a shoulder, arranged at an obtuse angle 45 to the upper portion of the cutter.

4. A check book having a cover provided with spaced pockets and a resilient check cutter having its terminals sprung into the said pockets and detachably secured by the 50 same to the said cover, the intermediate portion of the cutter being arranged to permit a check to be passed between it and the cover and adapted to be pressed against the check while the same is being cut.

In testimony whereof I affix my signature in presence of two witnesses.

JOHN F. SHOEMAKER.
